LUGGAGE LOCK

Frederic K. Heyer, Stamford, Conn., assignor to
The Yale & Towne Manufacturing Company,
Stamford, Conn., a corporation of Connecticut

Application July 7, 1943, Serial No. 493,711

20 Claims. (Cl. 70—350)

This invention relates to a lock, and more particularly to a lock adapted for use on luggage.

One feature of my lock resides in the novel arrangement of a locking and mounting member whereby to yield a very desirable form of locking structure, and a locking structure of particular utility in luggage. As a further feature of this part of my invention, my novel arrangement of a locking member and mounting member yields a lock of extremely pleasing form and of special utility in that it may be assembled to luggage without protruding greatly from the surface of the luggage.

A further feature of my invention resides in the arrangement of the locking mechanism per se of my lock, this locking mechanism preferably taking the form of tumblers. A feature of the invention resides in the arrangement of the parts whereby the tumblers may be operated by the flat portion of a key blade positioned in a special form of keyway. It is this feature of my invention that contributes the compact and highly desirable arrangement of the parts.

As a still further feature of my invention I utilize a novel arrangement of tumblers, and novel means for projecting the tumblers, and limiting their projection. The tumblers and the drivers preferably employed therewith, are adapted when set with their parting lines in a proper plane, to allow for a rotation of the locking member controlled by the tumblers to an unlocking position. It is a further feature of this part of my invention that the key may be removed in the unlocking position of the locking member, a camming opening being provided for the movement of the locking tumblers as the key is withdrawn. As still a further feature of this part of my invention, as the locking tumblers move into the camming opening, at least one of the drivers moves into a detent opening in the locking member to retain the locking member yieldingly in its unlocking position. The camming opening, as a further feature of the invention, is arranged to cam the tumblers towards the keyway upon rotation of the locking member so as to allow the locking member to rotate back to locking position, and into position to allow the tumblers and drivers to interlock as will be understood by those skilled in the art.

In describing my invention, I prefer to describe it as embodying pin tumblers, but those skilled in the art will appreciate that other types of tumblers may readily be utilized and adapted, and that it is not essential to certain parts of my invention that tumblers and drivers be employed.

I have thus described generally the more important feature of my invention in order that my contribution to the art may be better understood and in order that the relation of my contribution to the prior art may be better comprehended. I do believe that my invention is broad and valuable and should not be limited to the structural details that I have designed and here set forth. Also, while I have described generally several important features of my invention, there are other important features that will be described particularly in the specification and will be claimed in the claims appended hereto.

Referring now to the drawing

Fig. 1 is a perspective view showing the lock of my invention applied to a suitcase, and with the key about to enter the keyway of the lock.

Fig. 2 is a vertical section along lines 2—2 of Fig. 1 showing the locking tumblers in locking position and maintaining the locking member against rotation.

Fig. 3 is a view exactly like Fig. 2 but illustrating the tumblers and locking drivers in release position.

Fig. 4 is a view taken at 90 degrees from the sections of Figs. 2 and 3 showing the locking member rotated into unlocking position, and the key still within the keyway of the locking member.

Fig. 5 is a section taken along lines 5—5 of Fig. 4.

Fig. 6 is a section taken along lines 6—6 of Fig. 2.

Fig. 7 is a perspective view of the locking disc member when examined from its underside.

Fig. 8 is a perspective view of the entire lock assembly shown considerably larger than in Fig. 1.

Fig. 9 is a perspective view of the key employed in my lock.

Referring now more particularly to the drawing, and first more especially to Fig. 1, I show a suitcase 10 formed with a lid 11 adapted to be locked in the position of Fig. 1. The locking mechanism of my invention is designated generally by reference numeral 12 and comprises a locking disc member 13 and a base or mounting member 14. The locking mechanism also utilizes a strike 15 that is secured to the lid 11 as through bars 16, and it is through the said strike that the lid 11 is locked, as will be described presently.

The means for securing the base member 14 to the suitcase are not shown because they may be of any conventional form well known in the art, and because they do not per se form part of my invention.

The locking disc 13 is formed with a locking

lug 17 as is best illustrated in Fig. 7, and this locking lug 17 cooperates with the lip 18 of the strike 15 to lock the strike in place as is best illustrated in Figs. 2 and 3. While I prefer a direct interlock between the disc 13 and strike 15, other forms of locking cooperation are quite within the scope of my invention. The locking disc 13 is formed with a central lug 20 internally threaded at 21, the central lug 20 forming the bearing for the locking disc 13 relatively to the base member 14, as shown in the drawing.

A screw stud 22 is threaded into the threaded opening 21 of the stud 20 to hold the locking disc 13 assembled to the base member 14, and a washer 23 on stud 22 serves as an anti-friction member. Obviously any other suitable means for rotatably mounting the locking disc 13 on the base member 14 may be utilized. A limit member 24 may be riveted to the base member 14 as best seen in Figs. 3 and 6, the ends of this limit stop co-acting with the ends 17a of the locking lug 17 as is quite apparent from the drawings and in that way limiting the rotation of the locking disc 13 on the base member 14.

In the particular form of lock shown, the locking disc 13 is formed with four bores 30 with which are aligned four bores 31 formed in the base member 14. Tumblers 32 and drivers 33 slide in the aligned bores 30 and 31, and are pressed upwardly in Figs. 2, 3 and 5 by leaf springs 34 secured as by staking at 35 in slots 36 in the base member, there being a slot 36 in communication with each of the bores 31 in which the drivers 33 are mounted. The upper ends of the tumblers 32 are adapted for cooperation with a key, and for this purpose the tumblers are projected into a key slot 37 formed in the locking disc 13. For simplicity of manufacture the key slot is formed by securing to the locking disc 13 a plate 38, the keyway 37 being defined by inner surface 38a of the plate 38, and an upper surface of the locking disc 13. The bores 30 in which the tumblers 32 slide extend into the keyway 37, so that the ends of the tumblers 32 are projected by springs 34 against surface 38a of the plate 38, the said surface 38a acting as a limit stop for the tumblers.

When the key 40 is inserted, its end surface 41 acts to depress the tumblers and drivers against the pressure of the several springs 34 until the key is fully inserted, and with its depressions 42 in alignment with the several tumblers 32. If the proper key is utilized, the tumblers and drivers will now assume the position of Fig. 3 with their parting line coinciding with the parting line between the locking disc 13 and the base member 14. It will now be possible to rotate the locking disc 13 relatively to the base member 14 into the position of Fig. 4. This action, of course, effects the movement of the locking lug 17 of the locking disc 13 away from locking engagement with the lip 18 of strike 15. The lid 11 may then move with the strike 15 relatively to the body of the suitcase 10. This movement of the strike relatively to the locking mechanism is well illustrated in Fig. 4.

The locking disc 13 is formed with what I call a detent slot 45, and when the locking disc is rotated to the position of Fig. 4 from the position of Fig. 3, the several drivers 33 will enter the detent slot 45 and thereafter yieldingly hold the locking disc 13 in its position of Fig. 4. The particular action of the drivers 33 is well illustrated in Fig. 5, and in Fig. 7 the shallow form of the detent slot 45 is also quite apparent.

Whenever it is desired to lock the strike 15 once again, it is quite easy to overcome the holding action of the drivers 33 and detent slot 45 and to rotate the disc 13 into locking position.

It is highly desirable that it be possible to withdraw the key 40 from the locking mechanism when the parts are in their unlocked position of Fig. 4. For the particular purpose the base member 14 is formed with a camming slot or opening 46 well illustrated in Figs. 4 and 6. As is quite apparent, this camming slot or opening 46 is in alignment with the several pin tumblers 32 when the locking disc 13 has been moved to unlocking position. The depth of the camming slot 46 is such that when the key 40 is moved outwardly of the key slot 37 the tumblers 32 may move into the camming slot 46 and outside the depressions 42 of the key, thereby allowing the key to be removed quite readily from the keyway. If, when the key is removed, it is desired to relock the mechanism, it is only necessary to move the strike 15 back to the position of Fig. 3 and rotate the locking disc 13. The locking disc 13 will rotate readily after the resistance of the drivers 33 and detent slot 45 is overcome, since the shape of the camming slot 46 is such as to cam the tumblers 32 upwardly and entirely within the bores 30 of the locking disc 13. As soon as the locking disc 13 returns to its position of Fig. 2, the drivers 33 will be propelled by their springs 34 into locking relation to the tumblers 32 and locking disc 13. The tumblers 32 will then again be pressed against the surface 38a of the plate 38 and available for key operation by key 40 as illustrated in Fig. 3.

While I have shown my invention as applied to a suitcase, and with the strike secured to the lid of a suitcase, other applications of my invention will be obvious to those skilled in the art. As an example, the strike 15 may be made as part of a slide fastener pull, or the flap of a brief case, etc., and locked in the same manner as herein set forth.

I believe that the construction and operation of my invention will now be quite apparent.

I now claim:

1. In a lock of the class described, a base member, a locking member rotatably mounted relatively to said base member, tumblers for effecting the locking of said locking member against rotation relatively to said base member, portions of said tumblers entering through bores of said locking member into a keyway extending longitudinally across said locking member at right angles to its axis of rotation on said base member, and springs pressing said tumblers against the side of the keyway opposite that side of the keyway through which the tumblers project into said keyway.

2. In a lock of the class described, a base member, a locking member mounted on said base member for rotation on a fixed axis relatively to said base member, tumblers positioned at each side of said axis on a line passing diametrically through said axis and perpendicularly thereto and effecting the locking of said locking member against rotation on said base member, portions of said tumblers extending into a keyway formed diametrically across said locking member perpendicularly to its axis of rotation on said base member, and leaf springs secured to said base member for pressing said tumblers against the side of the keyway opposite that side of the keyway through which the tumblers project into said keyway.

3. In a lock of the class described, a base member, a disc-like locking member, a shaft mounting said disc-like locking member for rotation on said base member on an axis positioned centrally and perpendicularly relatively to said disc-like locking member, tumblers for effecting the locking of said locking member against rotation on said base member, and portions of said tumblers extending into a keyway formed diametrically across said locking member at right angles to its axis of rotation on said base member.

4. In a lock of the class described, a base member, a disc-like locking member, a shaft mounting said disc-like locking member for rotation relatively to said base member on an axis positioned centrally and perpendicularly relatively to said disc-like locking member, tumblers for effecting the locking of said disc-like locking member to said base member, said tumblers being positioned at each side of said central axis on a line diametric of said disc and passing through said axis at right angles thereto, and portions of said tumblers extending into a keyway formed diametrically across said locking member at right angles to its axis of rotation relatively to said base member.

5. In a lock of the class described, a base member, a disc-like locking member, a shaft mounting said disc-like locking member for rotation relatively to said base member on an axis positioned centrally and perpendicularly relatively to said disc-like locking member, a series of tumblers and drivers movable parallel to said axis and normally spring pressed to interlock said disc-like locking member and base member, and portions of said tumblers extending into a keyway extending longitudinally across said locking member at right angles to its axis of rotation relatively to said base member.

6. In a lock of the class described, a base member, a disc-like locking member, means mounting said disc-like locking member for rotation on said base member on an axis positioned centrally and perpendicularly relatively to said disc-like locking member, a series of tumblers and drivers mounted in bores formed in said locking member and base member parallel to the said axis of rotation, the parting line of said tumblers and drivers corresponding to the parting line between said disc and base member when set to release said disc-like locking member for rotation, said tumblers projecting into a keyway extending perpendicularly to the tumblers and formed for a flat key, to be positioned so that one of the flat sides of the key sets said tumblers, and spring means pressing said tumblers toward the side of the keyway opposite that side of the keyway through which the tumblers project into said keyway and against the said flat side of the key.

7. In a lock of the class described, a base member, a disc-like locking member, means mounting said disc-like locking member for rotation relatively to said base member on an axis positioned centrally and perpendicularly relatively to said disc-like locking member, a series of tumblers for locking said disc locking member against rotation relatively to said base member, said tumblers projecting through bores of said disc-like locking member into a keyway of substantially rectangular cross section through one surface thereof, spring means for projecting said tumblers yielding toward the surface of said keyway opposite the surface through which the said tumblers project into said keyway, the said surfaces forming the wide surfaces of the keyway and defining with

opposed end narrow surfaces a keyway for a flat key, one of the flat sides of which rather than the edge is adapted for setting the tumblers.

8. In a lock of the class described, a base member, a locking member rotatably mounted on said base member, tumblers for effecting the locking of said locking member against rotation on said base member, and portions of said tumblers extending through bores of said locking member into a keyway formed diametrically across said locking member at right angles to its axis of rotation on said base member, said keyway having narrow end surfaces and wide upper and lower defining surfaces perpendicular to the axis of rotation of said locking member and through the lower one of which said tumblers project, whereby a flat key inserted into said keyway will have its flat side contacted by said tumbler.

9. In a lock of the class described, a base member, a locking member rotatably mounted on said base member, tumblers for effecting the locking of said locking member against rotation on said base member, and portions of said tumblers extending through bores of said locking member into a keyway formed diametrically across said locking member at right angles to its axis of rotation on said base member, said keyway having narrow end surfaces and wide upper and lower defining surfaces perpendicular to the axis of rotation of said locking member and through the lower one of which said tumblers project, and springs pressing said tumblers against the upper of said surfaces.

10. In a lock of the class described, a base member, a disc-like locking member, means mounting said disc-like locking member for rotation on said base member on an axis positioned centrally and perpendicularly relatively to said disc-like locking member, tumblers for effecting the locking of said locking member against rotation on said base member, and portions of said tumblers extending through bores of said disc-like locking member into a keyway formed diametrically across said locking member at right angles to its axis of rotation on said base member, said keyway having narrow end surfaces and wide upper and lower defining surfaces perpendicular to the axis of rotation of said locking member and through the lower one of which said tumblers project, toward the flat side of a key inserted in said keyway.

11. In a lock of the class described, a base member, a disc-like locking member, means mounting said disc-like locking member for rotation on said base member on an axis positioned centrally and perpendicularly relatively to said disc-like locking member, tumblers for effecting the locking of said locking member against rotation on said base member, portions of said tumblers extending through bores formed in said disc-like locking member into a keyway formed diametrically across said locking member at right angles to its axis of rotation on said base member, said keyway having narrow end surfaces and wide upper and lower defining surfaces perpendicular to the axis of rotation of said locking member and through the lower one of which said tumblers project, and springs pressing said tumblers against the upper of said wide defining surfaces.

12. In a lock of the class described, a base member, a locking member rotatably mounted relatively to said base member, tumblers for effecting the locking of said locking member against rotation relatively to said base member, portions of said tumblers extending into a keyway

formed diametrically across said locking member at right angles to its axis of rotation relatively to said base member, the proper positioning of said tumblers by a key in said keyway releasing said locking member for rotation relatively to said base member, and a camming opening in said base member into which said tumblers are projected as said key is withdrawn from the keyway after predetermined relative rotation of said members, the said camming opening camming the tumblers inwardly of said keyway to permit relative rotation of said members to locking position.

13. In a lock of the class described, a base member, a disc-like locking member, means mounting said disc-like locking member for rotation on said base member on an axis positioned centrally and perpendicularly relatively to said disc-like locking member, a series of tumblers and drivers mounted in bores formed in said locking member and base member parallel to the said axis of rotation, the parting line of said tumblers and drivers corresponding to the parting line between said disc and base member when set to release said disc-like locking member for rotation, said tumblers projecting into a keyway extending perpendicularly to the tumblers for positioning by a key inserted into said keyway, said base member having a camming opening into which said tumblers may be moved as the key is withdrawn from said keyway after predetermined rotation of said locking member relatively to said base member, the said camming opening camming the tumblers inwardly of said keyway to permit rotation of said locking member to locking position to realign said tumblers and said drivers.

14. In a lock of the class described, a base member, a disc-like locking member, means mounting said disc-like locking member for rotation on said base member on an axis positioned centrally and perpendicularly relatively to said disc-like locking member, a series of tumblers and drivers mounted in bores formed in said locking member and base member parallel to the said axis of rotation, the parting line of said tumblers and drivers corresponding to the parting line between said disc and base member when set to release said disc-like locking member for rotation, spring means projecting said tumblers into a keyway in said disc-like locking member for positioning by a key against the force of said spring means, said base member having a camming opening into which said tumblers may be moved as the key is withdrawn from said keyway after predetermined rotation of said locking member relatively to said base member, the said camming opening camming the tumblers inwardly of said keyway to permit rotation of said locking member to locking position to realign said tumblers and drivers.

15. In a lock of the class described, a base member, a disc-like locking member, means mounting said disc-like locking member for rotation on said base member on an axis positioned centrally and perpendicularly relatively to said disc-like locking member, a series of tumblers and drivers mounted in bores formed in said locking member and base member parallel to the said axis of rotation, the parting line of said tumblers and drivers corresponding to the parting line between said disc and base member when set to release said disc-like locking member for rotation, spring means projecting said tumblers into a keyway in said disc-like locking member for positioning by a key against the force of said spring means, said base member having a cam-

ming opening into which said tumblers may be moved as the key is withdrawn from said keyway after predetermined rotation of said locking member relatively to said base member, the said camming opening camming the tumblers inwardly of said keyway to permit rotation of said locking member to locking position to realign said tumblers and said drivers, at least one of the drivers projecting similarly into a detent opening in the said disc-like locking member upon rotation of said locking member into the position in which its tumblers may enter said camming opening, in which position said driver will yieldingly hold said disc-like locking member.

16. In a lock of the class described, a base member, a disc-like locking member, means mounting said disc-like locking member for rotation on said base member on an axis positioned centrally and perpendicularly relatively to said disc-like locking member, a series of tumblers and drivers mounted in bores formed in said locking member and base member parallel to the said axis of rotation, the parting line of said tumblers and drivers corresponding to the parting line between said disc and base member when set to release said disc-like locking member for rotation, said tumblers projecting into a keyway extending perpendicularly to the tumblers and formed for a flat key, one of the flat sides of which is adapted for the positioning of said tumblers, and spring means pressing said tumblers against the side of the keyway opposite that side through which they project into said keyway, said base member having a camming opening into which said tumblers may be moved as the key is withdrawn from said keyway after predetermined rotation of said locking member relatively to said base member, the said camming opening camming the tumblers inwardly of said keyway to permit rotation of said locking member to locking position to realign said tumblers and said drivers.

17. In a lock of the class described, a base member, a disc-like locking member, means mounting said disc-like locking member for rotation on said base member on an axis positioned centrally and perpendicularly relatively to said disc-like locking member, a series of tumblers and drivers mounted in bores formed in said locking member and base member parallel to the said axis of rotation, the parting line of said tumblers and drivers corresponding to the parting line between said disc and said base member when set to release said disc-like locking member for rotation, said tumblers projecting into a keyway extending perpendicularly to the tumblers and formed for a flat key, one of the flat sides of which is adapted for the positioning of said tumblers, and spring means pressing said tumblers against the side of the keyway opposite that side through which they project into said keyway, said base member having a camming opening into which said tumblers may be moved as the key is withdrawn from said keyway after predetermined rotation of said locking member relatively to said base member, the said camming opening camming the tumblers inwardly of said keyway to permit rotation of said locking member back to locking position to realign said tumblers and said drivers, at least one of the drivers projecting similarly into a detent opening in the said disc-like locking member upon rotation of said locking member into the position in which its tumblers may enter said camming opening, in which position said driver will yieldingly hold said disc-like locking member.

18. In a lock of the class described, a disc-like base member, a disc-like locking member, means mounting said disc-like locking member for disc to disc rotation on said base member on an axis positioned centrally and perpendicularly to the disc-like locking member, a series of drivers and tumblers mounted in aligned bores of said base and locking members formed parallel to the axis of rotation of said locking member on said base member and in communication with a keyway, springs on said base member pressing the drivers and tumblers so as to maintain the key contacting ends of the tumblers against the surface of said keyway opposite the surface through which said bores communicate with said keyway, said tumblers being adapted for positioning by depressions formed in one of the flat surfaces of a flat key in said keyway to release said disc-like locking member and its tumblers for rotation relatively to the base member and its drivers, said base member having a camming opening into which said tumblers may be moved as the key is withdrawn from said keyway after predetermined rotation of said locking member relatively to said base member, the said camming opening camming the tumblers inwardly of said keyway to permit rotation of said locking member to locking position to realign said tumblers and said drivers.

19. In a lock of the class described, a disc-like base member, a disc-like locking member, a shaft

5 mounting said disc-like locking member for disc to disc rotation on said base member on an axis positioned centrally and perpendicularly to the disc-like locking member, tumblers for effecting the locking of said locking member against rotation on said base member, and portions of said tumblers extending into a keyway extending longitudinally across said locking member at right angles to its axis of rotation on said base member, said keyway having narrow ends and wide upper and lower surfaces for housing a flat key with the flat of the key in said keyway contacted by the ends of the tumblers extending into said keyway.

10 20. In a lock of the class described, a disc-like base member, a disc-like locking member, means mounting said disc-like locking member for disc to disc rotation on said base member on an axis positioned centrally and perpendicularly to the disc-like locking member, tumblers for effecting the locking of said locking member against rotation on said base member, and portions of said tumblers extending into a keyway extending longitudinally across said locking member at right angles to its axis of rotation on said base member, said keyway having narrow ends and wide upper and lower surfaces for housing a flat key with the flat of the key in said keyway contacted by the ends of the tumblers extending into said keyway.
